UNITED STATES PATENT OFFICE.

JAMES H. REED, OF SWAMPSCOTT, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

STOP MECHANISM.

Application filed October 14, 1922. Serial No. 594,458.

This invention relates to stop mechanisms for automatically stopping a machine at a definite point in its cycle of operations when the usual starting treadle is released or 5 other mechanism operated to release the clutch and disconnect the machine from its source of power.

Mechanisms of this character operate to stop and start a machine quite suddenly, and 10 in the case of heavy machines, or those operating at relatively high speed, a considerable blow is struck upon the stop mechanism when the latter is operated to stop the machine, such a blow not only imposing 15 a considerable shock upon the stop mechanism, but reacting upon the machine itself to the detriment of the latter. A similar blow is struck when the machine is started.

The present invention has for its objects 20 to provide a construction in which both of these blows will be cushioned and in which the starting operation is a relatively gradual one, and also to provide stopping means in which the driven mechanism is given, 25 through a suitable brake, a movement resisting force which is directly proportional to the momentum of the parts to be stopped, so that, the harder the blow struck, the greater will be the force with which the 30 brake is applied to stop the mechanism.

The foregoing and other objects of the invention, together with means whereby the same may be carried into effect, will best be understood from the following description 35 of a preferred embodiment thereof illustrated in the accompanying drawings. It will be understood however that the particular construction and application described and shown have been chosen for illustrative 40 purposes merely, and that the invention, as defined by the claims hereunto appended, may be otherwise practiced without departure from its spirit or scope.

In said drawings:

45 Fig. 1 is a somewhat conventionalized view, in side elevation, of the head of a shoe sewing machine having the invention applied thereto, the clutch being shown as fully engaged, but with the stop finger in a 50 position to disengage the same upon a further rotary movement of the shaft in the direction of the arrow.

Fig. 2 is an enlarged side elevation, part-

ly in section, of the clutch and stop mechanism shown in Figure 1, the clutch being 55 shown partly disengaged.

Fig. 3 is a transverse section taken substantially on the line 3—3 of Fig. 2.

Fig. 4 is a detail longitudinal sectional view, taken substantially on the line 4—4 60 of Fig. 2, and on a slightly reduced scale greater, however, than that of Fig. 1.

Fig. 5 is a transverse section taken substantially on the line 5—5 of Fig. 4.

In Figure 1 is indicated the head 10 of 65 a shoe sewing machine having a suitable frame in which is journalled a main shaft 11 driven by power from a suitable source delivered through a belt (not shown) to a driving pulley 12 loose on said shaft. The 70 pulley 12 has a hub 45 on which is rotatably mounted a ring 44 held in position on said hub by a collar 46 secured to the hub 45 and received in the countersunk end of said ring. The pulley 12 carries a laterally projecting 75 pin 47 which enters an arcuate slot or groove 48 in the adjacent face of the ring 44, said slot containing a spring 49 interposed between said pin and one end of the slot, whereby said pin is normally held in engagement with the opposite end of the slot, as shown in Fig. 5. The ring 44 constitutes the driving element or member of a clutch, the driven member of which comprises a hub 13 fast upon the shaft 11, as by means 80 of a suitable set screw 14 (see Figure 4). Guided in the hub 13 for longitudinal movement parallel to the shaft 11 is a sliding bolt 15 adapted at its forward end to engage a recess 16 in the ring 44, thereby connecting 90 the driving and driven members for rotation in unison. The bolt 15 is acted upon at its outer end by a spring 17 housed in a recess in the outer end of an enlarged portion 29 of the hub 13, said spring tending normally 95 to force the bolt into engagement with the recess 16 and connect the clutch members. The bolt 15 is formed with a head 19 which cooperates with the wedge-shaped end 20 of a stop member or finger 21, adapted to enter 100 a groove 22 in the hub 13 and engage the head 19 when the parts are rotated in the direction indicated by the arrows, causing said head to be forced backwardly or to the left in Figure 2, thereby withdrawing the 105 bolt 15 from the recess 16, and disconnecting

the clutch members. At the base of the wedge-shaped end 20 the stop member 21 is formed with a shoulder 23, which, after the bolt has been withdrawn to disconnect 5 the clutch members, is engaged by the bolt head 19, thereby positively stopping the driven member and shaft. The stop finger or member 21 is pivoted by a bolt or cap screw 24 to a lug 28 on the machine frame 10 and may be swung upon its pivot into and out of the groove 22, and to this end is provided with an extension 25 connected by a link 26 to a suitable foot treadle 27 or other operating device whereby said finger may 15 be swung out of the groove 22 to permit the spring 17 to engage the clutch, said finger being moved into the groove 22 to disengage the clutch and stop the machine when the treadle is released and lifted by the usual 20 treadle lifting spring 30.

When the bolt 15 is projected into the recess 16 by the spring 17 to engage the clutch, the machine is at rest so that a blow is struck by the end of the recess 16 upon 25 the end of the bolt. This blow is cushioned by the spring 49, which is compressed permitting the ring 44 to yield angularly with respect to the pulley 12 and the machine to be started gradually. As the inertia of the 30 parts is overcome, and the machine picks up speed, the spring 49 again expands, said spring being of sufficient strength to transmit the necessary power when the machine is running.

35 The opening 31 in the stop member 21 to receive the pivot bolt 24 is elongated in a direction generally tangential to the hub 13, and particularly to that portion thereof at the bottom of the groove 22 which is engaged by said stop finger when the latter is in a position to stop the machine. When, therefore, the shoulder 23 on said stop finger is struck by the head 19 of the clutch bolt, said stop finger will be moved tangentially 40 of the hub under the impact. Such movement is resiliently resisted by a spring pressed abutment in the form of a plunger 33 slidably mounted in a tubular guide 34 carried by the frame of the machine, said 45 plunger being backed by a spring 35 having an adjusting screw 36 by which the tension of said spring may be adjusted. The axis of the plunger 33 and guide 34 is substantially in alinement with the slot 31, so that said plunger tends to yieldingly resist the tangential movement of the stop finger 21 caused by the impact of the bolt head 19, thereby cushioning said impact.

50 The enlarged portion 29 of the hub 13 constitutes a brake drum which is encircled by a brake band 38 one end of which is fixed by a pin 39 to a hanger 40 loosely hung on the shaft 11 and adjustably secured to the machine frame by a bolt 41 which passes 55 through a slot 42 in said hanger. The oppo-

site end of the brake band 38 is secured by a pin 43 to the stop finger 21 at a point eccentric to its pivot 24.

In the foregoing construction, it will be seen that when the stop finger 21 is moved outwardly to permit the clutch to be engaged, the brake band 38 will be loosened, but that when said finger is swung inwardly to stop the machine, said brake band will be tightened upon the brake drum 29. It will also be seen that when the shoulder 23 of the stop finger is struck by the bolt head 19, causing said finger to yield against the pressure of the spring 35, this yielding movement, which is in a direction generally tangential to the clutch hub, will cause said brake band to be further tightened to an extent determined by the force of the blow. Since this blow is proportional to the momentum of the parts as transmitted through the driven member or hub 13, it will be seen that the brake band 38 constitutes means for applying to the driven member a movement resisting force which is proportional to such momentum, the final tightening of the brake 90 being effected by the driven member itself acting through the stop finger. The adjustable hanger 40 enables the force with which the brake is applied to be manually adjusted in accordance with the requirements and to 95 compensate for wear.

As will now be seen, the invention above described provides a stop mechanism wherein the blows struck by the sudden stopping and starting of the machine are so completely cushioned as to avoid undue shock to the parts. It will also be seen that the blow struck in stopping is itself made to apply a force tending further to stop the movement of the part which strikes the 105 blow, which stopping force is directly proportional to the force of the blow struck. It has been found in practice that, by the use of the invention described, all starting and stopping shocks are completely eliminated, while permitting the machine to be quickly and accurately stopped at the desired point in its cycle of operations.

110 What I claim is:—

1. The combination with driving and driven members, of a bolt carried by said driven member for connecting the same with said driving member, a yieldingly mounted stop finger for withdrawing said bolt and stopping said driven member, and a brake 115 for said driven member connected with said stop finger and operated by the yielding movement thereof.

2. The combination with driving and driven members and a headed bolt carried by said driven member and movable into and out of engagement with said driving member, of a stop finger having a wedge portion to engage the head of said bolt and withdraw the same from engagement with said 120

125

driving member, said finger having also a shoulder to engage said bolt and stop the rotation of said driven member, a support on which said stop finger is pivoted for movement into and out of a position to engage said bolt as said driven member is rotated, said stop finger having also a movement on said support in the direction of the blow of said bolt on said shoulder, a yielding 10 abutment for resiliently resisting said last named movement and cushioning said blow, and a brake band fixed at one end and encircling a portion of said driven member, the opposite end of said band being connected to said stop finger.

3. The combination with a frame and a shaft journalled therein and having driven and driving members respectively fast and loose thereon, of means for operatively con-

nected said members, a stop finger for releasing said connecting means and stopping said driven member, a brake drum on said driven member, a hanger loosely supported by said shaft and adjustably connected with said frame, and a brake band secured at one end to said hanger and at the other end to said stop finger, said brake band encircling said brake drum.

4. A clutch mechanism comprising a pulley having a hub, a ring rotatably mounted on said hub and formed with a recess and an arcuate slot, a pin carried by said pulley and entering said slot, a spring interposed between said pin and one end of said slot, and a driven member having a sliding bolt 30 adapted to enter said recess.

In testimony whereof I affix my signature.
JAMES H. REED.
